UNITED STATES PATENT OFFICE.

HALBERT K. HITCHCOCK, OF TARENTUM, PENNSYLVANIA.

METHOD OF APPLYING ABRASIVES TO GRINDING APPARATUS.

1,099,366.

Specification of Letters Patent.

Patented June 9, 1914.

Application filed July 31, 1911, Serial No. 641,482. Renewed March 27, 1914. Serial No. 827,774.

To all whom it may concern:

Be it known that I, HALBERT K. HITCHCOCK, a resident of Tarentum, in the county of Allegheny and State of Pennsylvania, have invented a new and useful Improvement in Methods of Applying Abrasives to Grinding Apparatus, of which the following is a specification.

This invention relates to a method of handling sand or other abrading material for use with grinding machines, such as used in the grinding and smoothing of plate glass.

The object of the invention is to simplify the handling of the material and delivery of the same to the grinding machine mixed with water.

In the manufacture of plate glass the plates are ground by the use of sand or similar abrasive mixed with water. Considerable quantities of abrading material must be used, and in the larger plants this is brought to the place of use by a clam shell bucket or the like, and deposited in a hopper or bin, from which it is delivered from time to time to the grinding tables. It has also been proposed to provide apparatus for grading the sand while in suspension in water; *i. e.* separating it into grades of different sizes or characteristics, and very recently such apparatus has been installed in one or two plants. In the most up to date plants, the sand is taken from the sand pile and mechanically transferred to a hopper or bin and stored until required for the grinding operation. When deposited in a hopper, the damp sand packs tightly therein and arches or bridges over the discharge opening and will not without assistance run out when the discharge outlet is opened.

Inasmuch as these hoppers advantageously converge toward the bottom and the sand is deposited therein from overhead, the mass packs in quite tightly so that arching and clogging in the hopper is the rule.

The purpose of the present invention is to facilitate the handling of sand and similar abrading material under the conditions stated and in a manner to permit it to be carried to the place of use by clam shell buckets or other mechanical means, and deposited from overhead into a suitable hopper, from which it is delivered in a continuous stream mixed with liquid, in which

condition it can either go directly to the 55 grinding table or to suitable grading apparatus.

In the accompanying drawings, Figure 1 is a diagrammatic elevational view of apparatus for carrying out the method; Fig. 2 60 is a side elevation on an enlarged scale of the lower end of the sand hopper and valve closing the same; Fig. 3 is a front elevation of the same; and Fig. 4 is a vertical section through the same.

In the drawings, 1 represents the hopper for receiving the sand and storing the same until needed for use. This hopper is open at the top and is adapted to have the sand delivered thereinto by any suitable overhead means, the drawings showing both a clam shell bucket 2 and a conduit 3 for this purpose, the clam shell bucket being used for dry and wet sand, and the conduit when the sand is carried in suspension in water, 75 in which latter case the superfluous water is withdrawn through an overflow pipe 15.

The hopper is of modified conical form, decreasing in size from its top downward and having its rear or bottom wall 4 sloping on a rather flat angle. The sand deposited into such hopper from the clam shell bucket or other overhead delivery means is liable, unless absolutely dry, to pack tightly and wedge toward the bottom, and this evil is increased if the sand is fairly damp or wet, which is the usual condition. The discharge opening 5 is from the lower, small end or apex of the hopper, and consequently the heavy, wet sand falling into the hopper 90 from above, packs so tightly that it invariably forms a bridge or arch over the discharge opening.

The discharge opening 5 is closed by means of a suitable valve, shown at 6, of 95 general segmental shape and provided with side plates or wings 7 which are secured to a pivot pin or pintle 8 mounted in a suitable bearing in the casting 9 forming the lower part of the hopper. The valve 6 is formed on the arc of a circle struck about the center of the hinge pin or pintle 8, and is adapted to be either swung underneath the discharge opening to close the same as shown in Fig. 2, or swung forwardly and upwardly to 105 open the discharge opening, as shown in Fig. 4.

The valve may be actuated by any suit-

able means. The drawings show for this purpose a suitable actuating shaft or key 10 fitting the end of the pivot pin or pintle 8 and preferably secured thereto, such as by set screw 11, and provided with arm 12, lying between lugs 13 on one of the side plates or wings 7 of the valve. The shaft or key 10 can be actuated or rotated by any suitable means, either by hand or mechanical means. Usually it is operated by providing the same with a suitable lever or arm 14 which projects downwardly a sufficient distance to be readily operated by the attendant. Any other suitable valve 15 may be used for controlling the discharge opening.

In order to cause the sand to run freely and smoothly from the hopper notwithstanding the bridging or arching thereof, I provide suitable fluid pressure connections, preferably hydraulic, for removing the material from underneath. This may be accomplished in various ways, and in a crude way can be effected by merely turning the nozzle of a hose through the discharge opening 5 when the valve 6 is open. As illustrated in the drawings, this is accomplished by means of a stream of water supplied through pipe 16 to a small chamber 17, cored out in the casting 9 and from which an opening 18 leads upwardly into the hopper, so that a jet of water can be thrown up against the arched or bridged mass of sand and gradually wash away and remove the same from below. Another opening 19 is also preferably provided and so arranged as to project a jet of water across the discharge opening and break up or dislodge any sand which may mass at this point; or the valve 6 may be adjusted to discharge the required volume of mixture and the space below the abrasive may be filled with liquid from the pipe 16, so that when the liquid reaches the latter the abrasive will drop down through the liquid to the discharge opening 6 and be discharged. I prefer to use the jet described as under ordinary circumstances the movement of the abrasive from the hopper can be initiated or stopped by simply starting or stopping the flow of liquid from the pipe 16, while in the other case it is necessary to fill up the space below the abrasive before the abrasive will begin to discharge, and it is necessary to open the valve 6 and shut off the liquid and wait for the abrasive still in suspension to be discharged.

In case the abrasive is frozen, either hot water or steam or both are introduced through the pipe 16 so that the abrasive is thoroughly thawed out before being applied on the grinding table. The practicability of this manner of removing packed sand from the hopper will be readily apparent. It also has the advantage of removing the

sand in a stream of water so that it does not reach the grinding table or grader, if the latter is used, in a lumpy condition, but is in much better condition either for grinding directly or grading than if delivered from the hopper in a substantially dry condition.

The sand can be taken directly from the hopper to the grinding table, which is shown at 20 and which may be of the usual or any desired form of plate glass grinding tables. The table shown is mounted upon a bottom shaft 21 and driven by means of gear 22 or other suitable means on said shaft, and is provided with the usual runners 23. The gutter 24 around the table catches the sand and water as it is discharged from the table and returns it to the grader or leads it to the sewer. A suitable pipe or trough 25 conducts the sand and water to said table, preferably between the runners, as is usual.

In the arrangement shown in the drawings, the sand is delivered from the hopper 1 to a grader for dividing it into grades of different sizes or characteristics. This grader may be of various forms but is shown as an inverted cone shaped vessel 27 adapted to receive the sand at the top and having connections for projecting upwardly therein a stream of water, such as a pipe or other connection 28 at its bottom, substantially the same as shown and described in my Patent No. 934,441, September 21, 1909. This grader is not illustrated in detail, and it will be understood that the particular construction and arrangement thereof may vary within considerable limits. The trough or pipe 25 conducts the graded material from the grader 27 to the grinding table. The sand and water coming from the grinding table through the gutter 24 is preferably led to a pit or sump, not shown, from which it is returned to the grader and is re-graded.

30 represents the overflow pipe for carrying to the sewer the mud and very fine and scummy substances in the grader.

31 represents a fine sand cone for finishing, as described in the companion application Serial No. 641,483 filed concurrently herewith, but as it forms no part of the invention claimed herein, it is not described.

In carrying out the invention, the sand is deposited in hopper 1 and is removed therefrom in quantities as desired by merely opening valve 6 and turning on the water through pipe 16, which excavates the packed sand from below and carries it mixed with water to the grader 27. Not being lumpy or in large masses it reaches the grader in the best possible condition for grading without violently agitating the mixture in the grader or splashing, as is the case when the relatively dry sand is deposited directly into the grading vessel. In the cone 27 it is suit-

ably graded and then taken grade by grade in the proper sequence to the grinding table and there used.

It is obvious that with the invention described, the arching or packing of the sand in the hopper does no harm, and indeed is rather a benefit as it can be removed rather slowly in small quantities by the jet of water, thereby securing more uniform delivery to the grader. Clogging or packing obviously is not an evil with the invention described.

Various changes in the construction and arrangements of parts can be made without departing from the spirit of the invention, and I wish it understood that no limitations are to be imposed upon the terms of the claims hereinafter made on account of either the specific apparatus illustrated in the drawings or described in the specification.

20 What I claim is:—

1. The method of handling abrading material, which consists in depositing the material in a mass in a hopper, introducing into the bottom of said hopper liquid in sufficient quantity to excavate the packed abrading material from below and form a mobile mixture of liquid and abrading material, and withdrawing the mixture of liquid and abrading material from said hopper.

2. The method of handling abrading material, consisting in depositing the material in a mass and from above in a hopper having a bottom opening, and introducing into said hopper from below a stream of water, to thereby attack the mass from below and wash or remove the material from the bottom of the hopper.

3. The method of handling abrading material, consisting in depositing the material in a mass in a hopper converging downwardly and provided with an opening in

its bottom, and injecting into the hopper from below and through said opening a stream of liquid and thereby slowly and uniformly removing the mass of material. 45

4. The method of handling abrading material for grinding machines and the like, consisting in depositing the material in a mass in a hopper converging downwardly 50 and provided with an outlet in its bottom, injecting into the hopper from below a stream of water and thereby slowly and uniformly removing the mass of material, and then conducting the material to the grinding 55 machine.

5. The method of handling abrasive material for grinding machines and the like, consisting in depositing the material in a mass in the hopper converging downwardly 60 and provided with an outlet in its bottom, injecting into the hopper from below a stream of water, and thereby slowly and uniformly placing the material in suspension in the water and removing it from the hopper, and then conducting the material while still in suspension in water to the grinding 65 machine.

6. The method of handling abrading material for grinding machines, consisting in 70 depositing the sand in a mass in a hopper provided with an outlet opening in its bottom, injecting into the hopper a stream of water and thereby removing the mass of material, then grading such material while 75 in suspension, and finally conducting the material in grades to a grinding machine.

In testimony whereof, I have hereunto set my hand.

HALBERT K. HITCHCOCK.
